SOLDERLESS ELECTRICAL CONDUCTOR CLAMP

Hugh W. Batcheller, Newton Highlands, Mass.

Application December 15, 1949, Serial No. 133,081

5 Claims. (Cl. 173—269)

1

This invention relates to an electrical connector for connecting the end of a wire to a conductor or terminal on electrical apparatus such as switches. It is an object of the invention to provide a connector which is compact in structure so that it occupies but little space, is efficient in providing a good electrical connection, and is simple and inexpensive to manufacture. Control switches for electric ranges, for example, require a considerable number of terminals to which wires must be connected so that several stages of heating can be had as desired. In the limited space within a range which must contain such switches and their connections, it is important that the connections be compact as well as reliable.

According to the present invention, a connector is provided which consists essentially of a single piece of spring metal which is bent in the form of a U-shaped loop to project through a hole in the terminal to which the connection is to be made, the end of the wire to be connected being passed through the loop which projects through the hole, as hereinafter described. Only enough wire need be stripped of its insulation to project through the loop and be gripped thereby. This is much less than the length of wire required to bend around a screw as in the ordinary connector.

For a more complete understanding of the invention, reference may be had to the following description thereof and to the drawing, of which—

Figure 1 is a perspective view of a connector embodying the invention, the connector being shown as it appears in use;

Figure 2 is a plan view of the spring member of the connector;

Figure 3 is a front elevation of the spring member;

Figure 4 is a side elevation of the same, a portion being broken away to show in section; and

Figure 5 is a sectional view of the connector with a wire being inserted therein and portions of a tool which may be employed to spring the connector to receive a wire.

For convenience of description in the following specification and in the claims, the connector will be described as being in the position occupied as shown in Figure 5, that is, with the loop of the spring member projecting up through the hole in the conductor or terminal which is shown in a horizontal plane, but it is to be understood that in use the connector may occupy any desired position. The size of the connector is

2

considerably exaggerated in the drawing for clearness of detail; the actual size of the connector being scaled to the diameter of the wire which is to be connected.

Figures 1 and 5 show a plate 10 which is of conducting material such as metal sheet or strip stock and which may be a switch terminal or any other conductor. This plate or strip is provided with a rectangular hole 12 through which is thrust the loop portion 14 of a strip of spring metal such as spring steel, bronze, beryllium copper or an equivalent, this strip being bent into an inverted U-shape the end portions or wings 18 and 20 being bent outward and upward as indicated in Figure 3. The spring member 16 is assembled with the plate 10 by pushing the loop portion 14 up through the hole 12 until the extremities 22 and 24 of the spring 16 engage the under face of the plate 10, the hole 12 being just large enough to accommodate the loop 14. The loop 14 is so proportioned that when the spring member 16 is thus assembled with the plate 10, the width of the opening 26 of the loop which is above the plate 10 is substantially equal to the diameter of the wire 30 which is to be connected. The height of this opening 26 above the plate 10 is a little less than the diameter of a wire when the spring member 16 is unstressed.

In order to insert the end of the wire 30 through the opening 26, the spring member must be sprung to a shape such as is illustrated in Figure 5. This can be done by pressing down on the plate 10 at points adjacent to the hole 12 when the connector is resting on a fixed surface. When no fixed surface is convenient to support the connector, a tool may be employed such as a pair of pliers having jaws shaped as indicated in Figure 5, the jaw 32 being adapted to bear against the wings 18 and 20 of the spring member 16 so as to support the spring member from below, the other jaw 34 having two projections 36 and 38 adapted to straddle the loop 14 and to bear down on the plate 10 at points above the wings 18 and 20. Distortion of the spring member 16 to the shape shown in Figure 5 results in a sufficient increase in the height of the opening 26 through the loop to admit the wire 30. When the connector is then released, the wings 18 and 20 spring back as far as they can toward their unstressed position and thus draw the top of the loop portion 14 down into firm pressing engagement on the wire 30, the adjacent portions of the wire being thereby firmly pressed against the upper face of the plate 10 to make a good electrical connection. The connection may be

improved by plating the spring member 16 with silver, chromium, or the like. The plating provides an improved electrical conduction as well as protection for the spring member from corrosion.

As it is generally desirable to prevent the spring member 16 from dropping out of the hole 12 when there is no wire projecting through the loop to keep it in place, downwardly facing shoulders 40 are provided on one or both edges of the loop portion of the spring member, these shoulders being located above the level of the extremities 22 and 24 in such position as to rest on the upper face of the plate 10 when the spring member 16 is unstressed. In order to permit the assembling and disassembling of the spring member and plate when the former is provided with shoulders 40, the spring member is preferably provided with a central longitudinal slot 42 which extends throughout the entire loop portion and terminates near the ends of the wing portions 18 and 20. This slot enables the portions of the strip on opposite sides thereof to be sprung toward each other sufficiently to permit the loop to be inserted through the hole 12, the width of the hole being substantially equal to the width of the strip 16 at points below the shoulders 40. The spring member 16 is thus retained by the shoulders 40 in assembled relation with the plate 10.

In order to grip the wire 30 positively so as to prevent accidental disconnection, a sharp arcuate fin 44 is preferably provided along each lower edge of the curved portion of the loop 14. If the strip 16 is stamped from a sheet of spring steel or the like, the shearing cut which separates the strip from the sheet results in a sharp fin or burr along the edges of one face of the strip. In shaping the spring member 16, this fin or burr is accentuated along the central portion of the strip by curling the edges of the strip slightly downward to form the fin or fins 44, as shown in Figure 4. When the connector is released from the stressed position shown in Figure 5, the downward pull on the loop 14 causes the sharp fins 44 to dig into the wire 30 and thus to anchor it against accidental removal from the connector.

I claim:

1. An electric connector comprising a plate having a hole therethrough, a strip of spring metal bent to an inverted U shape with the end portions curved outward and upward, the loop of said U projecting up through said hole, the extremities of said strip bearing against the under face of said plate, the opening defined by the loop and plate having a height slightly less than its width when the strip is unstressed.

2. A connector as described in claim 1, the side edges of said strip at the top of said loop being slightly curled down providing sharp arcuate fins.

3. A connector as described in claim 1, the side edges of the loop portion of said strip having shoulders bearing on the upper face of said plate to maintain the strip and plate in assembled relation, said strip having a longitudinal slot terminating near the ends thereof whereby the portions of the strip on opposite sides of the slot can be pressed toward each other to narrow the loop portion of the strip and permit said shoulders to clear the edges of said hole.

4. A connector as described in claim 3, the side edges of said strip at the top of the loop each having a sharp arcuate fin projecting down therefrom.

5. A spring member for an electric connector, comprising a strip of spring metal bent into an inverted U shape with the end portions thereof bent outward and upward, said strip having a longitudinal slot therethrough terminating near the ends thereof and downwardly facing shoulders on the side edges thereof at a higher level than the extremities of the slot.

HUGH W. BATCHELLER.
